(57) **CLAIM**

The ornamental design for a LIGHT FRAME FOR AUTOMOBILE as shown and described.

DESCRIPTION

FIG. 1 is a perspective view of an outer frame of a LIGHT FRAME FOR AUTOMOBILE showing my new design.

FIG. 2 is a front elevational view of the outer frame of the LIGHT FRAME FOR AUTOMOBILE.

FIG. 3 is a rear elevational view of the outer frame of the LIGHT FRAME FOR AUTOMOBILE.

FIG. 4 is a left side view of the outer frame of the LIGHT FRAME FOR AUTOMOBILE.

FIG. 5 is a right side view of the outer frame of the LIGHT FRAME FOR AUTOMOBILE.

FIG. 6 is a top plan view of the outer frame of the LIGHT FRAME FOR AUTOMOBILE.

FIG. 7 is a bottom plan view of the outer frame of the LIGHT FRAME FOR AUTOMOBILE.

FIG. 8 is a perspective view from another angle of the outer frame of the LIGHT FRAME FOR AUTOMOBILE.

FIG. 9 is a magnified view of a portion of FIG. 8.

FIG. 10 is a perspective view of an inner frame of the LIGHT FRAME FOR AUTOMOBILE.

FIG. 11 is a front elevational view of the inner frame of the LIGHT FRAME FOR AUTOMOBILE.

FIG. 12 is a rear elevational view of the inner frame of the LIGHT FRAME FOR AUTOMOBILE.

FIG. 13 is a left side view of the inner frame of the LIGHT FRAME FOR AUTOMOBILE.

FIG. 14 is a right side view of the inner frame of the LIGHT FRAME FOR AUTOMOBILE.

FIG. 15 is a top plan view of the inner frame of the LIGHT FRAME FOR AUTOMOBILE.

FIG. 16 is a bottom plan view of the inner frame of the LIGHT FRAME FOR AUTOMOBILE.

FIG. 17 is a magnified view of a portion of FIG. 10.

FIG. 18 is a perspective view from another angle of the inner frame of the LIGHT FRAME FOR AUTOMOBILE.

FIG. 19 is a magnified view of a portion of FIG. 18.

FIG. 20 is a perspective view showing the assembling of the outer frame with the inner frame of the LIGHT FRAME FOR AUTOMOBILE.

FIG. 21 is a perspective view from another angle showing the assembling of the outer frame with the inner frame of the LIGHT FRAME FOR AUTOMOBILE.

FIG. 22 is a perspective view of the LIGHT FRAME FOR AUTOMOBILE.
